Primary Examiner — Cynthia M. Chin(74) *Attorney, Agent, or Firm* — Lando & Anastasi, LLP(57) **CLAIM**

The ornamental design for a handle, as shown and described.

DESCRIPTION

FIG. 1 is a top perspective view of the handle;

FIG. 2 is a top view of the handle;

FIG. 3 is a bottom view of the handle;

FIG. 4 is a right side view of the handle;

FIG. 5 is a left side view of the handle;

FIG. 6 is a front view of the handle; and,

FIG. 7 is a rear view of the handle.

The broken lines shown in the figures are for environmental purposes only and form no part of the claimed design.
